SWITCH

Marcus H. Rhodes, New Haven, Conn., assignor
to M. H. Rhodes, Inc., New Haven, Conn., a
corporation of Delaware

Application January 17, 1931, Serial No. 509,333

1 Claim. (Cl. 200—67)

This invention relates to switches, and with and 11 showing a second modification of the regard to certain more specific features, to electrical circuit making and breaking switches.

Among the several objects of the invention 5 may be noted the provision of an electrical switch of the class described which is quick and positive in its action, a switch in which the arrangement of parts is such that the assembly occupies a minimum of space, and which is accordingly adapted for multiple installations in 10 standard, single-switch type wall housings, and for installation in said single-switch housings in combination with one or more plug-receiving outlets and the like, a switch which contains a 15 minimum number of movable parts, and a switch wherein manual movement of the switch handle occasions a multiplied force as applied to the contacting means, whereby contact is made and broken with a snap action which reduces arc-forming tendencies. Other objects will be in 20 part obvious and in part pointed out hereinafter.

The invention accordingly comprises the elements and combinations of elements, features of construction, and arrangements of parts which 25 will be exemplified in the structure hereinafter described, and the scope of the application of which will be indicated in the following claims.

In the accompanying drawings, in which are illustrated several of various possible embodiments of the invention,

Fig. 1 is a front elevation of a face plate having a switch mounted thereon;

Fig. 2 is a side elevation of the plate and switch illustrated in Fig. 1;

Fig. 3 is a vertical cross-section taken on line 3—3 of Fig. 1;

Fig. 4 is a vertical cross-section taken on line 4—4 of Fig. 1;

Fig. 5 is an ideal section taken along lines 40 5—5 of Figs. 3 and 4;

Fig. 6 is a fragmentary horizontal section taken on lines 6—6 of Figs. 3 and 4;

Fig. 7 is a fragmentary horizontal section taken on lines 7—7 of Figs. 3 and 4;

Fig. 8 is a fragmentary vertical section taken on line 8—8 of Fig. 7;

Fig. 9 is a diagrammatic showing of the switch in closed-circuit position;

Fig. 10 is a diagrammatic showing similar to Fig. 10 showing the switch in open-circuit position;

Fig. 11 is a front elevation similar to Fig. 1 showing a modification of the invention; and,

Fig. 12 is a front elevation similar to Figs. 1

Similar reference characters indicate corresponding parts throughout the several views of the drawings.

Referring now more particularly to Figs. 1 and 2, numeral 1 indicates a face plate of the type in general use for wall mounting of electrical switches. A central opening 3 permits the control handle 5 of a switch 7 to extend outwardly 65 to an available manipulating position. Screws 9 hold the face plate 1 to the switch 7.

From the exterior, the switch 7 will be seen to comprise a mounting plate 11 (with which the face plate screws 9 engage) and a switch housing 13 having exterior connecting terminals 15 and 17 mounted thereon. The housing 13 is preferably formed of insulating material, such as bakelite (a phenolic condensation product) or the like. Screws 19 (see Figs. 3 and 4) hold 75 the housing 13 to the mounting plate 11.

The interior construction of the switch 7 will be seen in Figs. 3, 4, 5 and 6. The mounting plate 11 has extending at right angles therefrom a pair of sideward portions 21 and 23. A plate 25, which is shaped with substantially the same form as the housing 13, is attached to portion 21 by means of rivets or spot welding or the like as indicated at numeral 27 (Fig. 3). Mounted at one side in the plate 25, and at the other side in 85 the sideward portion 23, is a pin 29, upon which the control handle 5 is rotated.

The switch control handle 5 comprises a semi-circular portion 31 from which extends a knob 33 for manipulation purposes. The back, concealed (in the assembled switch) portion of the switch 5 is reduced in thickness as at numeral 35 (Figs. 5 and 6) and has a contour including a projection 37 having a nose 39 thereon, and a depression, or hollowed-out portion 41. The pin 95 29 upon which the handle 5 is rotated passes through the thin portion 35, in the region of the projection 37.

Mounted rigidly on the switch handle 5, embracing the thin portion 35 thereof, and extending into the depression 41, is a saddle member 43. This saddle 43 comprises a pair of legs 45, which fit snugly against the sides of the handle 5, and a cross-piece 47 at right angles to the legs 45. The pin 29 passes through the legs 45. The cross-piece 47 engages the nose 39 of the projection 37 of the switch 5, whereby the saddle 43 is, relative to rotation on the pin 29, fixed to the handle 5. That is to say, the saddle 43 is mounted on the handle 5 in a fixed, non-rotatable manner. 110

The cross-piece 47 is provided with a nose 49 which engages one end of a compression spring 51 to be described more in detail hereinafter.

Associated with the saddle 43 is a movement 5 limiting means for the handle 5 (see Fig. 6).

The movement limiting means per se comprises a flat h shaped piece 53, having parallel legs 55 and 57, and a single extending leg 59. The leg 55 passes loosely through a pair of holes 61 in the legs 45 of the saddle 43. The single extending leg 59 passes through a slot 63 having a predetermined length in the plate 25. Considering that the saddle 43 is fixed to the handle 5, and that the plate 25 is relatively a part of the stationary ground wherein the handle 5 rotates, it will be seen that engagement of the single extending leg 59 with the ends of the slot 63 limits the rotation or movement of the handle 5. The nature of the movement limiting means from a functional standpoint will be apparent by reference to Figs. 9 and 10, which are diagrammatic showings of the switch handle 5 at its extreme positionings.

Also mounted on the pin 29, in this instance 25 rotatably mounted, is a second saddle 65 embracing the saddle 43. The saddle 65, herein-after termed the hammer saddle, comprises a pair of relatively long legs 67, through which the pin 29 passes (loosely enough to permit of ready 30 rotation), and a hammer portion 69 at right angles thereto. The hammer portion 69 has a nose 71 thereon which engages the other end of the compression spring 51. Movement of the hammer saddle 65 is limited by a pair of ears 73 struck from the plate 25.

By reference to Figs. 9 and 10 it will be seen 35 that the saddles 43 and 65 together with the compression spring 51 comprise an overcentering toggle. In Fig. 9, motion of the handle 5 in an upward direction, through the saddle 43, compresses the spring 51 against the saddle 65, which is immovable because of its engagement 40 with the lower ear 73, until the saddles 43 and 65 pass the parallel position, at which time the compressed spring reacts to suddenly throw the hammer saddle 65 upwardly against the upper movement-limiting ear 73. A similar reaction and overcentering action causes the hammer saddle 65 to snap sharply from its Fig. 10 to its Fig. 9 45 position, when the handle 5 is moved downwardly from its Fig. 10 position.

In this manner, the switch functions to make and break connections with a quick, positive, snap action, and arcing and sparking are thus avoided.

The electrical connections in the switch will be 55 seen particularly in Figs. 4, 5 and 8. The exterior terminals 15 and 17 comprise, respectively, metallic strips 75 and 77 which are held to the housing 13 by means of screws, 79, and which receive 60 in threaded engagement screws 81. By means of the screws 81, exterior connections to the switch are made. The metallic strip 75 extends into the housing 13, spaced from the side wall thereof, and is provided with a slanting knife-edge contacting portion 83. The knife-edge portion 83 65 faces, relatively, in a backward-upward direction. The metallic strip 77 extends into the housing 13, also spaced from the side wall thereof, and is provided with a knife-edge contacting portion 85 70 similar to the contacting portion 81, but vertical and forwardly-facing in this instance.

Formed in interior of the back of the housing 13 is a protruding ear 87. A pin or shaft 89 passes through the side of the housing 13 and threadedly 75 engages the ear 87 (see Fig. 5). On the pin 89

is rotatably mounted a contactor bar-anvil assembly 91. The parts of the assembly 91 are non-rotatable or otherwise movable relative to each other, but the assembly as a whole rotates freely on the pin 89.

The assembly 91 comprises an anvil piece 93 and a contactor bar 95, together with suitable spacing washers, all mounted on a sleeve 97 through which passes the pin 89. The anvil piece 93, preferably formed of insulating material, includes a notch 99 which engages the hammer portion 69 of the hammer saddle 65 (see Fig. 4). The contactor bar 95 comprises a pair of spring-metal strips 101 shaped to engage and disengage, by rotation on the pin 89, the knife-edge contacting strips 83 and 85. The relative shape of the bar 95 and the spacing of the contacting strips 83 and 85 will be apparent from Fig. 4.

As the hammer saddle 65 snaps from one position to the other, as described hereinbefore, its engagement with the notch 99 in the anvil piece 93 causes the assembly 91 to rotate, as a whole, on the pin 89, and consequently causes the contactor bar 95 to rotate into and out of contact with the pieces 83 and 85. Thus making and breaking 100 of an electrical connection from terminal 15 to terminal 17 is effected in a sudden, snap-acting manner by simple movement of the switch control handle 5.

It will be seen that substantially all of the moving parts of the switch described lie approximately in one plane. Further, because of the design of the various parts and the intensified snap action provided, it is not necessary that any of the parts be very thick laterally. For these reasons, and 105 others, the switch of the present invention can readily be built in a very narrow form. In the particular embodiment described, the overall thickness of the switch need not greatly exceed three-quarters of an inch.

This novel thinness feature is an important advantage of the present invention. Because of such thinness, two or more switches may be mounted in a single existing switch box in a home, for example, upon alteration or redesign 110 of the house wiring. Fig. 11 illustrates the appearance of a face plate of standard one-switch size having mounted thereon two of the switches comprising the present invention. It is to be understood that more than two switches, with 115 proper design, might similarly be mounted on a standard single switch size face plate.

The invention may also be used on a standard single switch size face plate in combination with a number of outlets 103, as illustrated in Fig. 12. Thus, where it is desired to add outlets to an existing electrical installation, by means of the present invention such an end may be secured without changing the existing switch housings or tearing out walls or the like.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

A switch comprising a control handle rotating about a center, a saddle mounted on said handle and immovable relative thereto, a second, movable saddle rotating about said center, a com-

pression spring between said saddles, a pair of electrical terminals, a contactor bar, and an anvil member associated with said contactor bar, said anvil member having a lost motion notch therein, 5 said notch receiving the free end of said second-named movable saddle whereby motion of said saddle effects making and breaking of contact be- tween said terminals by means of said contactor bar, with a hammer blow, means transforming the rotary movement of said handle into linear movement, and means limiting the extent of said linear movement whereby to limit the movement of said handle. 30
